ABSTRACT

The output signal of a laser at a frequency V_f is mixed in a metal point contact diode with the output of a klystron having a variable frequency V_m . Because of the diode's non-linearities, the current flowing through the diode will contain and reradiate sideband components at frequencies $V_s = V_f \pm V_m$. Simultaneously, the diode is subjected to a reference signal with a fixed frequency having a harmonic which falls at a frequency close to one of the sideband frequencies V_s . A beat note is produced which fluctuates in frequency due to the instability of the laser frequency V_f . The beat note frequency is compared with a stable source and an error signal corresponding to the fluctuations is obtained which in turn is used to adjust V_m to compensate for the instability in V_f , whereby the frequency V_s is stabilized to a degree equal to that of the reference source. Additionally, the frequency of the sideband is determined to the same degree of precision. This information is extremely important and useful in making frequency measurements in the infrared region where it is difficult to produce a beat note by standard techniques of mixing a high harmonic of a known microwave signal with an unknown high frequency due to the low power of such a high harmonic. Here, harmonics of the components of stabilized laser sideband are used as intermediate step frequencies to bridge the gap between the microwave and visible regions.

BY

METHOD OF GENERATING A SIGNAL WITH A FREQUENCY BETWEEN 10^{11} AND 10^{15} HZ WITH EXTREME FREQUENCY STABILITY

This invention was made in the course of work performed under contracts with the U.S. Air Force and the U.S. Army.

FIELD OF INVENTION

This invention relates generally to infrared frequency mixing and frequency stabilization and measurement techniques.

PRIOR ART

The sources of coherent radiation with wavelengths between 300 and 1/10 micron are principally lasers. The frequency stability for free running gas or semiconductor lasers is between one part in 10^4 and one part in 10^7 . There are no general methods of stabilizing laser frequencies to a high degree of accuracy. However, there are techniques applicable to special cases such as those developed by John Hall of the Bureau of Standards, and those described by Javan and Freed in Applied Physics Letters, July 15, 1971, "Standing Wave Saturation Resonances in the CO_2 10.6μ Transitions Observed in a Low Pressure Room Temperature Absorber Gas." These techniques can be used to stabilize particular lasers to a high degree of accuracy and can be used as references in conjunction with the techniques taught by applicants' inventions.

SUMMARY OF INVENTION

In view of the limitations in achieving a high degree of frequency stability in the infrared and far infrared range, one object of applicants' invention is to provide a method of generating sideband laser signals with frequencies in the infrared and far infrared range with a stability far exceeding that obtainable with known techniques.

It is another object of applicants' invention to provide a method of making absolute frequency measurements in the infrared and far infrared region.

These and other objects are met by processes comprising:

1. mixing a laser frequency V_f with a microwave frequency V_m to produce a sideband frequency $V_s = V_f \pm V_m$,
2. mixing the sideband frequency V_s with a harmonic of a fixed microwave reference source, said harmonic falling close to the sideband frequency, thereby producing a beat note,
3. comparing the beat note frequency with a stable source and obtaining an error signal corresponding to the fluctuations in the beat note due to the laser instability.
4. utilizing the error signal to adjust frequency V_m to compensate for the changes in V_f with an unknown higher frequency, whereby the unknown frequency is determined from the resultant beat note frequency and the laser sideband frequency V_s .

Further objects and a better understanding of the apparatus thereof will become more apparent with the following description taken in conjunction with the accompanying drawing showing a diagrammatic view of the processes.

PREFERRED EMBODIMENT

In the accompanying drawing, the output radiation from a laser, e.g., a 337 HCN gas laser is mixed in a diode with an arbitrary frequency from a microwave source, e.g., 10 GHz from an X-band klystron. Typically, the mixing is accomplished with a metal to metal point contact diode with a 2 micron diameter cat whisker having an electrochemically etched point, a metal base, and a means for adjusting the contact pressure between the whisker and base. Such a diode is more fully described by V. Daneu, D. Sokoloff, A. Sanchez and A. Javan, "Extension of Laser Harmonic Frequency Mixing Techniques Into the $9\ \mu$ Region With an Infrared Metal Point Contact Diode," Applied Physics Letters 15, 398 Dec. 1969. Because of the diode's non-linearities, the far infrared frequency current flowing through the diode will contain and reradiate sideband components. If we let V_f represent the laser frequency and V_m represent the X-band microwave frequency, then the diode will contain and reradiate sideband components at frequencies $V_s = V_f \pm V_m$.

It should be noted that the frequency stability of V_f is about one part in 10^6 and that as V_f fluctuates V_s will fluctuate correspondingly as the fluctuations of V_m are relatively insignificant. Of course, V_f may be tuned over several megahertz by mechanically moving one of the laser interferometer mirrors, but this is a relatively slow process which occurs with a considerable time lag and phase shift. On the other hand, V_m may be tuned over much wider bandwidths by tuning the microwave source. In the case of a klystron, this is easily achieved by applying an electrical voltage to the klystron reflector. This type of tuning has a fast response time and occurs with very little lag and phase shift.

Simultaneously with the mixing of the laser frequency and the arbitrary microwave frequency, the diode is subjected to the output of a microwave reference source with a fixed frequency. This frequency is chosen such that a harmonic falls close to the sideband frequency. In our example, a V-band klystron operating in the 70 GHz range would have a thirteenth harmonic falling close to the sideband component resulting from the mixing of the 337μ laser frequency and the 10 GHz frequency produced by the X-band klystron. In fact, the V-band klystron is set so that a beat note is amplified by a 40 MHz IF amplifier as shown in the accompanying drawing. The bandwidth of the amplifier is several megahertz in order to accommodate the frequency fluctuations of the beat note which results from the instability of the laser frequency. If the stability of the laser is one part in 10^6 and its output is approximately 10^{12} Hz, then its fluctuations range up to 10^6 Hz thereby determining the necessary bandwidth requirement of the IF amplifier.

The fluctuations of the beat note are sensed by comparing the beat note frequency with a stable source. In our example, we compare the 40 MHz beat note with the frequency of a stable 40 MHz crystal controlled oscillator. This is accomplished by detecting the change in the phase of the beat note signal with respect to the stable source in a phase detector. This technique is well known in the art as phase locking. This phase detector sends out an electrical correctional signal pro-

portional to the difference in phase between the two input signals. This correction signal is fed back to the X-band klystron reflector thereby changing its output frequency V_m to compensate for the changes in V_f , whereby V_f is stabilized and the beat note frequency becomes phase locked to the stable source.

Since it is possible to use a 40 MHz reference source whose stability exceeds a fraction of a cycle, this method will then achieve phase locking of the far infrared sideband frequency to within a fraction of a cycle compared with the reference frequency, the thirteenth harmonic of the V-band signal. The V-band source, in turn, can be made very stable. For instance its frequency can be phase locked by standard techniques against higher harmonics of a stable radio frequency source to an accuracy of one part in 10^{11} or better. Hence, the sideband infrared frequency is correspondingly stabilized to an enormous and here-to-far unknown stability.

Additionally, the absolute frequency of the sideband is known to the same precision. It is equal to the frequency of the harmonic of the reference frequency plus or minus the beat note frequency, depending upon whether the harmonic is higher or lower than the sideband. This, of course, can be determined by standard techniques, as for instance by increasing the frequency of the reference signal and observing the change in the beat note frequency.

The knowledge of the absolute frequency is very important and useful in measuring unknown frequencies in the infrared region. In the infrared region, it is difficult to measure frequency by beating an unknown frequency with a high harmonic of a microwave reference signal due to the low power of the high harmonic. Hence, an intermediate step frequency is necessary to bridge the gap. Here the unstabilized laser frequency V_f and variable microwave frequency V_m may be utilized in the following manner. Suppose it is desired to determine the frequency of a 79μ water vapor laser. An unstabilized 311μ HCN laser frequency can be used to bridge the gap between a known microwave frequency and the unknown 79μ frequency. Initially, the output of the HCN laser and an X-band klystron operating around 9 GHz are mixed in a first diode with the fourteenth harmonic of a V-Band klystron operating at 70 GHz. A beat note frequency is obtained and phase locked to a stable source by controlling the X-band klystron as described above. The sideband difference frequency $V_s = V_f - V_m$ is accurately determined according to the teachings supra. The components of V_s , that is the unstabilized 311μ HCN laser frequency and the compensated 9 GHz microwave signal, are then mixed in a second diode with the output of the 79μ water vapor laser. In this process, the difference frequency of the fourth harmonic of the 311μ HCN laser and the 9 GHz klystron frequency, $4V_f - 4V_m$, lies very close to the 79μ water vapor laser thereby producing a beat note frequency. Since the beat note frequency can be accurately measured and since the difference between the fourth harmonic of V_f and fourth harmonic of V_m is known, the frequency of the water laser can be easily determined.

It is important to note that only the components of the sideband laser difference frequency are utilized, not the reradiated sideband signal. Hence, by using an

unstabilized 311μ HCN laser frequency, the bridge between the microwave region and far infrared has been bridged. Indeed, by repeated applications and extensions of these principles, one can readily see that absolute frequency measurements can be made into the infrared region. Further by utilization of this method and known bulk crystal techniques, the chain can be extended well into the visible region.

It should be noted that in the above description the sideband frequencies V_s were described as $V_f \pm V_m$. In general, sideband frequencies equal to $nV_f \pm qV_m$, where n and q are integers, are reradiated. However, when n and q are greater than one, the output power is diminished.

If the output is low, the reradiated signal may be amplified. One means of accomplishing this is to focus the reradiated signal into a parallel beam by a lens or other means onto one end of a long discharge tube which exhibits gain at the frequency of the signal. For instance, in our example, a HCN laser at 337μ and a microwave input of 74 GHz would produce a reradiated sideband frequency from the diode at 311μ . A HCN laser exhibits gain at 311μ . Hence, if the reradiated signal is focused on a discharge tube containing HCN gas at an appropriate pressure, the signal will be amplified. One limitation in this method is that at infrared frequencies the gain exhibited in discharge tubes is small. For instance, the gain of HCN laser at 311μ is about 10 - 15 percent per meter. Hence if the reradiated signal is at low power, a very long discharge tube might be required to obtain appreciable amplification.

Another method of amplifying the signal would be to use a regenerative type amplifier. One example of this class is a conventional discharge tube bounded by two parallel partially reflecting mirrors. If the reflectivity is chosen properly, the laser would be on the threshold of oscillation, but not quite oscillating. Under these conditions an input reradiated signal from the diode is strongly amplified.

The above stabilization technique may be modified by using a CO_2 gas laser operating in the 9.2μ region to 10.7μ region for a reference in place of a V-band klystron. The CO_2 laser's output at 9.3μ can be stabilized to one part in 10^{10} by techniques described by Javan and Freed in "Standing Wave Saturation Resonances in the CO_2 10.6μ Transition Observed in a Low Pressure Room Temperature Absorber Gas." New refinements in this process are currently in process to achieve a stabilization of one part in 10^{13} . This reference can be utilized to produce stable sideband frequencies for higher or lower frequencies. For example, the third harmonic of the difference frequency of the output of a 28μ water vapor laser and the output of an X-band klystron producing a 10 GHz signal lies very close to the 9.3μ frequency of the CO_2 laser. Hence, a beat note is produced by mixing in the diode the third harmonic of the sideband frequency and the 9.3μ reference signal. This is compared with a stable source whereby an error signal is produced to control the X-band klystron stabilizing the sideband difference frequency. Likewise, the second harmonic of the 10.6μ CO_2 laser frequency can be used as a reference to stabilize a sideband frequency of the 5.3μ transition of the CO_2 laser.

In the above illustrations a harmonic of the reference signal is compared with a laser sideband frequency or, a

harmonic of a sideband frequency is compared with a reference signal. If the sideband frequency to be stabilized and reradiated is far away from the reference source, it is desirable to modify this technique by using an intermediate step frequency as was illustrated above with respect to making absolute frequency measurements. As an example, suppose it is desired to stabilize a sideband of 28μ water vapor laser, one could utilize the 150th harmonic of a V-band klystron operating at 70 GHz; however, this harmonic would be very weak. It is therefore more advantageous to use an intermediate frequency. In stabilizing a 28μ sideband it is convenient to use the 337μ frequency as an intermediate frequency. The output from an HCN laser operating at 337μ and a klystron operating at 3 GHz are mixed in a first point contact diode with the thirteenth harmonic of a V-band klystron operating at 70 GHz. The best note frequency is obtained and phase-locked to a stable source by controlling the output of the klystron. The output frequency of the klystron and the output of the 337μ HCN laser are mixed in a second diode with the output frequency of a 28μ water laser and the output of an adjustable X-band klystron. Here the twelfth harmonic of the sum of the 337μ frequency and 3 GHz signal lies close to the sum of the 28μ laser and X-band frequency, i.e., the sideband of the 28μ laser. A beat note is produced and phase-locked to a stable source by controlling the frequency of the X-band klystron. Hence, the reradiated sideband of the 28μ laser is stabilized by utilizing an unstabilized lower laser frequency to bridge the gap between the high frequency water laser and low frequency V-band reference. It should be noted here that it is not necessary to use the sideband frequency at the intermediate lower laser frequency, but only its components, namely, the 3 GHz frequency and the unstabilized 337μ HCN laser. Likewise, this technique could be used to generate a stable sideband of the 337μ HCN laser using the stable 10.6μ output of the CO_2 laser as a reference and a 100μ unstabilized laser as an intermediate step frequency. Hence, one can readily see by using these techniques that stabilized sidebands and reradiated signals are achieved in the far infrared and infrared. The sidebands have a heretofore unknown stability.

What is claimed is:

1. A method of generating a stabilized sideband laser frequency in the far infrared and infrared range comprising:
  - a. mixing a laser frequency V_f with radiation from a source having an adjustable frequency V_m thereby producing sideband frequencies $V_s = nV_f \pm qV_m$, n and q being integers,
  - b. mixing the sideband frequency V_s with a reference signal having a harmonic whose frequency falls close to V_s , thereby producing a beat note,
  - c. comparing the frequency of the beat note with the frequency of a stable source, and obtaining an error signal responsive to the difference between the frequency of the beat note and the stable source,
  - d. feeding back the error signal to the source to adjust V_m such that the frequency of the beat note and standard are locked, whereby V_s remains constant to the same degree of stability as the reference source.

2. A method of generating a signal with a frequency in the far infrared and infrared range as recited in claim 1 wherein said laser frequency V_f is mixed with radiation from a microwave source having an adjustable frequency V_m and wherein said error signal is fed back to said microwave source, whereby a stabilized sideband $V_s = V_f \pm V_m$ is produced.
3. A method of generating a signal with a frequency in the far infrared and infrared range as recited in claim 1 wherein said laser frequency V_f is mixed with radiation from a radio source having an adjustable frequency V_m and wherein said error signal is fed back to said radio source.
4. A method of generating a signal with a frequency in the far infrared and infrared range as recited in claim 1 further comprising:
  - a. focusing the energy of the sideband frequency V_s into a parallel beam,
  - b. directing said beam into a discharge tube exhibiting gain at the sideband frequency,
  - c. amplifying said sideband frequency V_s in said discharge tube.
5. A method of generating a signal with a frequency in the far infrared and infrared range as recited in claim 1 further comprising:
  - a. focusing the energy of the sideband frequency V_s into a parallel beam,
  - b. directing said beam into a regenerative amplifier, said amplifier being on the threshold of oscillation but not quite oscillating,
  - c. amplifying said sideband frequency in said regenerative amplifier.
6. A method of generating a signal with a frequency in the far infrared and infrared range comprising:
  - a. mixing a laser frequency V_f with radiation from a source having an adjustable frequency V_m thereby producing sideband frequencies $V_s = nV_f \pm qV_m$, n and q being integers,
  - b. mixing the sideband frequency V_s with a reference signal having a harmonic whose frequency falls close to V_s , thereby producing a beat note,
  - c. comparing the frequency of the beat note with the frequency of a stable source, and obtaining an error signal responsive to the difference between the frequency of the beat note and the stable source,
  - d. feeding back the error signal to the source to adjust V_m such that the frequency of the beat note and standard are locked, whereby V_s remains constant to the same degree of stability as the reference source,
  - e. mixing an unstabilized laser frequency V_y with radiation from a source having an adjustable frequency V_x , thereby producing sideband frequencies $V_z = nV_y \pm qV_x$, n and q being integers,
  - f. mixing the sideband frequency V_z with a harmonic of V_m and an actual harmonic of V_f whose sum falls close to V_z , thereby producing a beat note,
  - g. comparing the frequency of the beat note with the frequency of a second stable source, and obtaining an error signal responsive to the difference between the frequency of the beat note and the second stable source,
  - h. feeding back the error signal to the source to adjust V_x such that the frequency of the beat note

and the second stable source are locked, whereby V_s remains constant to the same degree of stability as V_s .

7. A method of generating a signal with a frequency in the far infrared and infrared range comprising:

- a. subjecting the metal cat whisker of a first nonlinear point contact diode with laser radiation of frequency V_f , and with radiation from a microwave source having an adjustable output frequency V_m , said cat whisker having a diameter of the order of the wavelength corresponding to V_f , whereby a current is induced in and reradiated by the diode with sideband frequencies $V_s = nV_f \pm qV_m$, n and q being integers,
- b. simultaneously subjecting the cat whisker to an extremely stable microwave signal having a harmonic whose frequency falls close to V_s , thereby producing a beat note across the diode,
- c. comparing the frequency of the beat note with the frequency of a stable source and obtaining an error signal responsive to the difference between the frequency of the beat note and the stable source,
- d. feeding back the error signal to the microwave source to adjust V_m to phase lock the frequency of the beat note to the frequency of the stable source, whereby V_s remains constant to the same degree of stability as the microwave signal.

8. A method of generating a signal with a frequency in the far infrared and infrared range as recited in claim 7 further comprising:

- a. subjecting the metal cat whisker of a second nonlinear point contact diode with laser radiation of frequency V_x and with radiation from a microwave source having an adjustable output frequency V_u , said cat whisker having a diameter of the order of the wavelength corresponding to V_x , whereby a current is induced in and reradiated by the diode with sideband frequencies $V_s = nV_x \pm qV_u$, n and q being integers,
- b. simultaneously subjecting the cat whisker of said second diode to a harmonic of V_f and an equal harmonic of V_m whose sum falls close to V_s , thereby producing a beat note across said second diode,
- c. comparing the frequency of the beat note with the frequency of a second stable source and obtaining an error signal responsive to the difference between the frequency of the beat note and the second stable source,
- d. feeding back the error signal to the microwave source to adjust V_u to phase lock the frequency of the beat note to the frequency of the second stable source, whereby V_s remains constant to the same degree of stability as V_s .

9. A method of measuring an unknown far infrared or infrared frequency to a high degree of accuracy comprising:

- a. mixing an unstabilized lower laser frequency V_L with radiation from a microwave source having an adjustable frequency V_m , thereby producing sideband frequencies $V_s = nV_L \pm qV_m$, n and q being integers,
- b. mixing the sideband frequency V_s with a microwave reference frequency V_R having a harmonic whose frequency falls slightly lower than V_s , thereby producing a first beat note,
- c. comparing the first beat note frequency with the frequency of a stable source and obtaining an error signal responsive to the difference between the frequency of the first beat note and the stable source,
- d. feeding back the error signal to the source to adjust V_m such that the frequency of the first beat note and stable source are locked, whereby V_s remains constant to the same degree of stability as the reference source, said frequency V_s being equal to the harmonic of the microwave reference frequency, V_R , plus the first beat note frequency,
- e. mixing the unknown frequency with a harmonic of V_L and an equal harmonic of V_m whose sum falls slightly lower than the unknown frequency, whereby a second beat note frequency is produced and whereby said unknown frequency is determined as being equal to the sum of the harmonic of V_L and the equal harmonic of V_m plus the second beat note frequency.

10. A method of measuring an unknown far infrared or infrared frequency to a high degree of accuracy as recited in claim 9 wherein the harmonic of V_R falls slightly higher than V_s , whereby V_s is equal to the harmonic of V_R minus the beat note frequency.

11. A method of measuring an unknown far infrared or infrared frequency to a high degree of accuracy as recited in claim 9 wherein the mixing of the unknown frequency is with a harmonic of V_L minus a harmonic of V_m , and said unknown frequency is determined as being equal to the harmonic of V_L minus the harmonic of V_m plus the second beat note frequency.

12. A method of measuring an unknown far infrared or infrared frequency to a high degree of accuracy as recited in claim 9 wherein the sum of the harmonic of V_L and V_m falls slightly higher than the unknown frequency, whereby the unknown frequency is determined as being equal to the harmonic of V_L and harmonic of V_m minus said second beat note frequency.

13. A method of measuring an unknown far infrared or infrared frequency to a high degree of accuracy as recited in claim 9 wherein the harmonic of V_L minus the harmonic of V_m falls slightly higher than the unknown frequency, whereby the unknown frequency is determined as being equal to the harmonic of V_L minus the harmonic of V_m less said second beat note frequency.
